UNITED STATES PATENT OFFICE.

JULIUS WIESNER, OF MANCHESTER, NEW HAMPSHIRE, ASSIGNOR TO HIMSELF AND ZACHARIAS STOEPPLER, OF SAME PLACE.

POCKET-KNIFE.

SPECIFICATION forming part of Letters Patent No. 357,353, dated February 8, 1887.

Application filed November 27, 1886. Serial No. 220,058. (No model.)

To all whom it may concern:

Be it known that I, JULIUS WIESNER, of Manchester, in the county of Hillsborough and State of New Hampshire, have invented 5 a new and Improved Clasp-Knife, of which the following is a specification, reference being had to the annexed drawings, forming a part thereof, in which—

Figure 1 is a side elevation of my improved 10 clasp-knife, showing it in the position for being opened. Fig. 2 is a side elevation showing the knife partly open. Fig. 3 is a side elevation showing the position of the parts of the knife before being locked open. Fig. 4 15 is a side elevation of the knife-blade and a portion of the handle, showing the stud in the side of the blade, and representing the curved slot in the cheek-plates of the handle for limiting the movements of the blade. Fig. 5 20 represents in perspective the ends of the cheek-plates of the handle, and in end elevation the pivoted end of the blade. Fig. 6 represents in perspective the fastening-latch 25 of the handle, and Fig. 7 shows in perspective the end of the cheek-plates of one side of the handle with the latch-operating spring attached thereto.

Similar letters of reference indicate corresponding parts in all the views.

30 The object of my invention is to provide a knife without a back-spring, in which the blade will be held rigidly in an open or closed position.

My invention consists in the arrangement 35 and combination of parts, as hereinafter more fully described and claimed.

The knife-blade A is provided with a shank, 40 a, of uniform thickness and rounded at the end, and furnished with an aperture, b, for receiving the pivotal screw b' of the knife, and the studs c c', projecting from opposite sides of the shank at diametrically-opposite sides of the aperture b, and at equal distances from said aperture. The cheek-plates d d' are provided 45 with apertures e e', for receiving the screw b', upon which the blade A is pivoted, and in the said cheek-plates are formed semicircular slots f f', for receiving the studs c c', projecting from opposite sides of the knife-blade.

The cheek-plates d d' are provided with the 50 usual bolsters, g g', and are furnished with cheeks h h', of wood, ivory, or other suitable material. The cheek-plate d is provided with a movable end piece, i, having a shank, j, which slides in a groove in the inner surface 55 of the cheek h, and is provided with a slot, k, which receives the screw l, passing through the cheek d and screwed into the cheek h, and serving the double purpose of holding the cheek and of limiting the motion of the end 60 piece, i. The side of the end piece, i, adjoining the cheek-plate d is provided with an oblong cavity, m, for receiving the spring n, attached to the outer surface of the cheek-plate, and bearing against one of the walls of the cavity 65 m, tending to push the end piece, i, toward the cheek h.

The end piece, i, is provided with an arm, o, 70 projecting from its inner face at right angles and furnished with a T-shaped head, which is received in a recess, p, of corresponding form, in the end of a distance-piece, q, secured to the cheek-plate d'. The distance-piece q extends along the rear edge of the cheek-plate d, in the position usually occupied by the back- 75 spring of an ordinary clasp-knife.

When it is desired to open the clasp-knife, the movable end piece, i, is pushed outward, withdrawing the T-headed arm o from the recess p, when the cheek-plate d and parts attached thereto are turned, with the screw b' as a pivot, until the edge of the cheek-plate at the end of the slot f is brought into engagement 80 with the stud c, projecting from the side of the shank of the knife-blade, when by the continued forward movement of the cheek-plate d the knife-blade will be turned, together with the cheek-plate, until the stud c strikes the edge of the plate d' at the end of the slot f', when the knife will be in its open position, 85 and may be fastened by allowing the T-headed arm o of the end piece, i, to slip into the recess p, and thus lock the cheek-plate with the studs c c' at the ends of the slots f f'.

The knife is closed by disengaging the T- 90 headed arm o from the recess p in the distance-piece q and reversing the operation just described.

Having thus fully described my invention, I claim as new and desire to secure by Letters Patent—

The springless clasp-knife comprising the 5 knife-blade provided with studs on opposite sides of its shank arranged at diametrically-opposite sides of its pivot, the cheek-plates provided with semicircular slots, the spring-

pressed sliding end piece provided with the T-headed arm, and the recessed distance piece, substantially as shown and described.

JULIUS WIESNER.
